Patented Dec. 10, 1918.

2 SHEETS—SHEET 2.

UNITED STATES PATENT OFFICE.

ANDREW ANDERSON, OF CROOKSTON, MINNESOTA.

COMBINATION TOOL-CHEST AND WORK-BENCH.

1,287,175.

Specification of Letters Patent. Patented Dec. 10, 1918.

Application filed February 15, 1918. Serial No. 217,420.

To all whom it may concern:

Be it known that I, ANDREW ANDERSON, a citizen of the United States, residing at Crookston, in the county of Polk and State 5 of Minn., have invented certain new and useful Improvements in Combination Tool-Chests and Work-Benches; and I hereby declare that the following is a full, clear, and exact description thereof, reference being 10 had to the accompanying drawings, which form part of this specification.

This invention is a novel combination tool chest and work bench for use by carpenters and mechanics; and its object is to provide a 15 durable and convenient apparatus which can be folded compactly as a chest for transportation; or can be readily expanded as a work bench when desired.

The invention includes a novel construction 20 and connection of boxes forming the main parts of the apparatus; a novel arrangement of covers whereby additional top space or work shelves is provided; novel means for interlocking the boxes; novel 25 foldable legs; and other novel details of construction and combinations of parts all hereinafter more fully explained with reference to the accompanying drawings; and the features and parts for which protection is desired 30 are summarized in the claims.

In said drawings:

Figure 1 is a perspective view of the complete apparatus adjusted as a work bench.

Fig. 2 is a reverse view of Fig. 1 with one 35 box cover closed.

Fig. 3 is a perspective view partly broken showing the boxes with the lids raised.

Fig. 4 is a view of the apparatus folded into a chest and closed.

40 Fig. 5 is an inverted bottom plan view showing one of the foldable legs open.

Fig. 6 is a similar view showing the leg partly folded.

Fig. 7 is a detail view of one of the hinges 45 connecting the boxes.

Fig. 8 is a detail sectional view illustrating the method of locking the drawers.

Fig. 9 is a detail showing the cover locking device.

50 Fig. 10 is a detail showing the interlocking edges of the supplemental covers 1^s and 2^s.

Fig. 11 is a detail.

The combined tool chest and work bench 55 comprises two similar sized boxes 1 and 2, each substantially built preferably of wood

and having closed ends and outer sides, and preferably provided with depending bottom flanges 1^b, 2^b respectively, so that the bottoms 1^b, 2^b of the boxes are slightly elevated 60 above the surface on which the boxes rest.

Box 1 is provided with a cover 1^b hinged to one side thereof and with a shallow top compartment 1^e having a bottom plate 1^j. Beneath compartment 1^e are a plurality of 65 drawers; two 1^e, 1^f, being shown, which drawers are inserted through openings in the inserside of the box (or side opposed to box 2 when the chest is closed). Said drawers may be of usual or any desired construction 70 and are shown as supported on suitable guides or bars attached to the ends of box 1 in the usual manner.

Box 2 is provided with a cover 2^b, top compartment 2^e having a bottom plate 2^j, and 75 with three drawers 2^e, 2^f, 2^g being shown arranged beneath compartment 2^e and supported on suitable guides on the ends of the box as usual.

Preferably, drawers 1^e, 1^f are so made that 80 when closed their outer sides lie about one half inch within the surface of the adjacent parts of the side of box 1; and drawers 2^e, 2^f, 2^g are preferably so constructed that when closed their outer edges project about a half 85 inch beyond the surface of the adjacent parts of the side of box 2 so that when the boxes are turned side by side (see Fig. 4) the projecting ends of the drawers in box 2 enter the recess in box 1 left by the inset 90 drawers therein; and thus the drawers interlock the boxes against relative vertical or lateral movement, like a tenon and socket.

The drawers may be locked when closed by inserting one leg of any ordinary carpenter's square S, into suitably formed grooves or notches 1^h, 2^h in the ends of the drawer slides 1^u, 2^u and between the slides and adjacent side of the box, (see Figs. 3 and 8) which grooves registering when the drawers 100 are closed; and the other leg of the angle lying within the compartment (1^e or 2^e).

The tops 1^b, 2^b may be fastened when closed by any suitable lock preferably mortise locks as indicated at 1^k, 2^k in the drawings. Top 1^b may be provided with a disappearing bench stop 1ⁿ of any suitable kind. 105

One end of a bar 3 may be pivotally secured to the cover 1^b by a bolt 3^a (see Fig. 3). Said bar is provided with a head 3^b to which 110 a clamping screw 3^e may be detachably attached. Bar 3 may be turned to a posi-

- tion at right angles to the cover, as indicated in dotted lines in Fig. 3 and engaged with a notch 3^a in front of the box, and project out of the compartment 1^c, and a clamping screw 3^b may be attached to this head and be supported thereby in convenient position to engage and hold the work, when the boxes are disposed so as to form a work bench, (see Fig. 1).
- 10 The boxes 1 and 2 are hinged together at their adjacent inner corners by means of suitable hinges so that the boxes can be relatively swung either into end to end position (Fig. 1) or side by side position (Fig. 4).
- 15 Preferably I use hinges having angle arms 4 (see Fig. 7) which can be screwed to the corners of the boxes and form a strong reinforced angularly braced hinge attachment; and these hinge members 4 have eyes trans-
- 20 fixed by pintles 4^a. If desired, the boxes could be disconnected by removing said pintles.
- The boxes are provided with supplemental covers 1^s, and 2^s adapted to overlie tops 1^b, 2^b, when closed (see Figs. 4 and 9). Each cover (1^s, 2^s) is preferably composed of sheet metal (see Fig. 9) and hinged to the rear side of the boxes by angle hinges 5^a, (Fig. 2) so that the covers 1^s, 2^s may be
- 25 turned outward at one side of the boxes and lie below the plane of the covers 1^b, 2^b and form a shelf or shelves, (as indicated in Figs. 1 and 2). Said supplemental covers may be supported in position as shelves by any suitable means; preferably by brackets 5^e that are detachably engaged with retainers of any suitable kind, on the outer or rear sides of the boxes 1 and 2 as indicated at 5^f Fig. 2. Said covers may be lined with
- 30 boards 5 to protect tools laid thereon when used as shelves. Said brackets can be readily detached when the supplemental covers are not to be used as shelves, and stored in compartment 1^c or 2^c.
- 35 The inner or free edge of covers 2^s is channeled, as at 2^m (Fig. 10) so that when the apparatus is folded into a chest, edge 1^m of cover 1^s will overlie the channel and form a tight joint and prevent water entering between the boxes.
- 40 Each box is preferably provided at each end with a foldable leg; which may be formed, (as shown in Figs. 5 and 6) of a main leg member 6 having a top bar 6^a attached by hinges 6^d to the bottom of the box within the base flange; and to this leg 6, is hinged a member 6^e which can be swung out in line with the leg 6 and form a bracing extension thereof (see Figs. 1 and 2)
- 45 and may be held in this position by a button 6^a or other suitable fastening. The leg 6 may be held in operative position by a brace 6^e hinged thereto as shown and adapted to be extended at right angles thereto
- 50 under a block 6^f attached to the bottom of

the box (see Fig. 5). When the apparatus is to be converted into a chest, the brace 6^e and extension 6^f can be folded against the insides of the leg 6 and the latter as indicated in Fig. 6 and then the whole may be folded against the bottom of the box within the flange 1^a.

When the boxes are swung into line to form a tool chest as indicated in Fig. 1, they may be held in this position by means of a U-shaped clip 7 that may be engaged with notches 7^a in the top of the adjacent ends of the boxes (see Figs. 3 and 11). When the boxes are to be folded as in Fig. 4, this clip may be removed and placed in one of the compartments or drawers.

The supplemental covers may be locked to and with the main covers by means of a hasp 8 attached to the cover 1^s, 2^s and having an angular perforated part 8^a adapted to project under the main cover when the cover is closed and engage a pintle 8^b (see Figs. 3 and 9) so that when the main cover is locked the supplemental cover will be also locked.

The drawers may be arranged to accommodate an assortment of tools, in practice I provide the upper drawer on left side with places for saws, one for each saw; the lower drawer on left side is for planes. The three drawers on the right are for smaller tools and light hardware such as screws, brads, etc.; the trays or compartments on top under bench covers are for such tools as are not used every day; and they are also large enough to contain overalls.

When the boxes are swung into line with legs folded (as in Fig. 3) the apparatus can be moved through an opening approximately 12 inches by 22 inches; and when arranged as a tool chest, Fig. 4 it is no longer than an ordinary carpenter's tool chest.

What I claim is:

1. A combination tool chest and work bench, comprising two boxes hinged together so that they can be swung side by side, or end to end; one box having a projecting drawer and the other a recess so that when the boxes are side by side the projecting drawer will engage the recess.

2. A combination tool chest and work bench, comprising two boxes hinged together at their adjacent corners, so that they can be swung side by side, or end to end; said boxes having drawers, those in one box being inset and those in the other box projecting so that when the boxes are side by side the projecting drawers will engage the recess formed by the inset drawers, substantially as described.

3. A combination tool chest and work bench, comprising two boxes hinged together so that they can be swung side by side, or end to end; each box having a top, and a hinged supplemental cover overlying

the top; said covers having edges adapted to form a tight joint when the boxes are arranged side by side as a chest.

4. A combination tool chest and work bench, comprising two boxes hinged together at their adjacent corners, so that they can be swung side by side, or end to end; each box having a hinged top, and a hinged supplemental cover overlying the top and means for fastening the tops and covers, said covers having edges adapted to form a tight joint when the boxes are folded side by side as a chest.
5. In a combination tool chest and work bench, a box having drawers, and drawer slides, said slides being constructed for engagement with the angle of a square, whereby the drawers can be locked when closed, substantially as described.
6. A combination tool chest and work bench, comprising two boxes hinged together at their adjacent corners, so that they can be swung side by side, or end to end; said boxes having drawers, and drawer

slides and guides, said slides and guides being constructed for engagement with the angle of a square, whereby the drawers can be locked when closed, substantially as described.

7. In combination with a box, a foldable leg attached to each end thereof, and comprising a member hinged to the bottom of the box and adapted to be folded thereunder, an extension hinged to said member, and a brace hinged to said member, said extension and brace being foldable against the member and therewith under the box, substantially as described.

8. In combination work bench and tool chest, a box having a hinged cover, and a notch in one side with a bar hinged to the cover and adapted to be turned so as to project out of the box through said notch, and support a clamp, substantially as described.

In testimony that I claim the foregoing as my own, I affix my signature.

ANDREW ANDERSON.
